US0D1045061S

(12) **United States Design Patent** (10) **Patent No.:** **US D1,045,061 S**
(45) **Date of Patent:** **** Oct. 1, 2024**

(54) **FIREPLACE TONG**

(71) Applicant: **Chaosen Wang**, Xinyi (CN)

(72) Inventor: **Chaosen Wang**, Xinyi (CN)

(**) Term: **15 Years**

(21) Appl. No.: **29/812,727**

(22) Filed: **Oct. 24, 2021**

(30) **Foreign Application Priority Data**

Oct. 18, 2021 (EM) 008728059-0003

(51) **LOC (14) Cl.** **23-03**

(52) **U.S. Cl.**

USPC **D23/407**

(58) **Field of Classification Search**

USPC D7/686, 687; D23/403, 407

CPC F24B 15/10

See application file for complete search history.
